third to Otto F. Koehn

Application January 17, 1944, Serial No. 518,638

9 Claims. (Cl. 15—144)

This invention relates to a paint brush and particularly to a handle therefor.

In painting various parts of a ship, equipment and appliances installed thereon, it has been found out that some of the surfaces which are partially hidden behind other parts, equipment and appliances, cannot be reached by an ordinary brush. Various means have been tried in connection with a brush to reach said inaccessible surfaces, but they proved to be inadequate.

It is the object of this invention to provide an articulated telescoping handle for a paint brush, or the like, which can be extended in length and the adjoining sections of which be set at an angle to each other, so as to get around an obstacle and reach a surface hidden therebehind.

Other objects and advantages will appear as the specification proceeds and the particular features of the invention will be specifically pointed out in the appended claims.

The invention is illustrated in the accompanying drawing in which:

Fig. 1 is a plan view of the brush.

Fig. 2 is a longitudinal cross-section of the brush, some parts being shown in elevation.

Fig. 3 is a bottom view of the brush.

Fig. 4 is a cross-section of the brush handle taken along the line 4—4 of Fig. 1.

Fig. 5 is a plan view of a front end of the keeper.

Fig. 6 is a plan view of a front end of a section of a brush.

Fig. 7 is an illustration showing one of the applications of the brush; and

Fig. 8 is a side view of the modified form of a brush handle.

In detail, my invention comprises a brush element 1 and an articulated telescoping handle 2. The brush element 1 has hair 3 imbedded in a metal holder 4 having a narrow neck 5 terminating with a ball 6.

The handle 2 has on its front end a ball socket 9 consisting of an upper member 10 and a lower member 11, both members being held together by a bolt 12 and a wing nut 13. The surface of the ball 6 and the inner surfaces of the socket 9 are preferably made rough to prevent the relative movement of the ball to the socket when the wing nut 13 is tightened up. The ball 6 and the socket 9 form a universal joint for the brush element 1 so that the latter may be placed into any angular position in relation to the handle 2.

The handle 2 consists of plurality of sections which are enclosed, with freedom to slide, in a

keeper 14. For the purpose of illustration, the handle 2 is shown in the drawing as having three sections, 15, 16 and 17, although it may have any number of the same without departing from the spirit of this invention.

The section 15 has on its front end the upper member 10 of the socket 9, which member is shown as made integral with the same. The rear end 18 of said section is reduced in thickness to one-half thereof and is rounded. The front end 19 of the section 16 is also reduced in thickness to one-half and both ends are connected by a pivot 20, which is affixed to the center of the end 19 and passes through a hole 22 in the end 18. The top of the pivot 20 is threaded and carries a nut 23 thereon to hold both ends together. The section 15 may be turned about the pivot 20 in any angular position in relation to the section 16.

Means is provided to interlock said sections in angular position, said means consisting of a small embossment 25 on the lower surface of the end 18 which fits in any one of the corresponding indentations 26 formed circumferentially on the upper surface of the end 19. The section 15 is turned around the pivot 20 to a desired position and until the embossment 25 fits into one of the indentations 26, whereupon the nut 23 is tightened up, thus holding both sections in fixed position.

The section 16 is connected with the section 17 in exactly the same way. The rear end 21 of the section 17 is connected with the keeper 14. The latter is preferably made in form of a channel with a bottom 30, two sides 31, each side having its upper portions 33 bent at right angle toward each other. The keeper 14 is closely fit around the sections 15, 16 and 17, but the latter may be easily moved in and out of the first.

The section 17 and the keeper 14 are connected by a bolt 34 which passes through a hole 35 in the end 21 of said section and a slot 36 extending through the length of the bottom 30 of said keeper. A nut 37 is provided on said bolt 34 to hold said section and keeper securely together.

The front end of the keeper 14 is rounded and the upper surface thereof is provided with a plurality of indentations 38 each of which is adapted to accept an embossment 39 formed on the lower side of the end 21 and to secure the section 17 in an angular position in relation to the keeper 14. It shall be noted that the sides 31 of the keeper 14 are cut off near its front end to enable the section 17 to swing about the bolt 34 at an angle more than 180°.

The handle 2, including the sections 15, 16 and

17 and the keeper 14 as well as bolts and nuts, may be made of any suitable material, such as any light metal, plastics, or the like.

In operation, the brush is used as an ordinary brush with the sections 15, 16 and 17 in contracted position as shown in Fig. 1. Whenever it is necessary to extend the handle of the brush, the nut 37 is unscrewed and the sections 15, 16 and 17 are pushed forward a desired distance and the nut 37 is tightened up. If necessary, one or more sections may be given an angular position. For that purpose the nuts 23 are unscrewed, the sections are turned around the bolts 20 into a desired position and the nuts 23 are tightened up. The sections may be pushed in extreme forward position as shown in Fig. 7 and given angular positions so as to permit the brush element 1 to get around an obstacle, such as a pipe 40. As is well known, certain pressure is applied upon a brush during painting. But in spite of such pressure the sections and the keeper will preserve their relative positions due to interlocking of the sections, as well as of the last section 17 and the keeper 14, by means of the embossments 25 and 39 and the indentations 26 and 38 respectively. The brush element 1 may also be given any angular position in relation to the section 15 due to the universal joint connection therewith.

Fig. 8 shows a modified form of my invention in which a separate brush element 50 having hair 51 embedded in a holder 52 is enclosed in a brush retainer 54 and securely held therein by means of bolts 55 passing through said holder 52 and retainer 54. The retainer 54 is connected by means of the neck 5 to the ball 6 of the universal joint between the brush element and the articulated telescoping handle as it has been described in detail heretofore. The advantage of the latter arrangement is that when the brush element 1 is worn out it is easily substituted by another one, or when a brush of a different shape, or size, is desired, the proper brush element is readily inserted in the brush retainer 54 and the brush is ready for immediate use.

Having thus described my invention, I claim:

1. A brush comprising a brush element, and a handle comprising a plurality of pivotally connected sections, a universal joint between said handle and the brush element, means at said pivotal connections and said universal joint to tighten the same in selected angular positions, a keeper adapted to slidably receive said sections when the same are in axial alignment, slidable means connecting the outermost section to said keeper to hold said last mentioned section in engagement with the keeper in all positions, and to tighten said connection therewith.

2. A paint brush comprising a brush element, a handle and a universal joint therebetween, said handle consisting of a keeper and plurality of sections pivoted to each other and slidable therein, said pivoted sections being adapted to form an extension of said handle and to assume angular positions in relation to each other and to the keeper.

3. A paint brush comprising a brush element,

a handle and a universal joint therebetween, said handle consisting of a keeper and a plurality of sections slidable in said keeper, each of said sections having an end reduced in thickness, and pivoted to the end of an adjoining section means in each of the adjoining ends for interlocking the same in angular positions to each other.

4. A paint brush comprising a brush element, a handle and a universal joint therebetween, said handle consisting of a plurality of sections pivotally connected to each other and adapted to take angular positions in relation to each other, means for interlocking said sections, means to tighten said sections in said angular positions and a keeper adapted to slidably receive said sections.

5. A paint brush comprising a brush element, a handle and a universal joint therebetween, said handle consisting of a plurality of sections pivotally connected to each other and adapted to take angular positions in relation to each other, means for interlocking said sections, means to tighten said sections in said angular positions, a keeper adapted to slidably receive said sections, a bolt connecting one of said sections to said keeper, a longitudinal slot in said keeper in which said bolt is adapted to slide, and means for interlocking the last mentioned section with said keeper in angular positions thereto.

6. A paint brush comprising a brush element, a handle, and a universal joint therebetween, said handle consisting of a keeper and plurality of pivoted sections slidable in said keeper, each of said sections and said keeper having means for interlocking the same in angular positions to each other, said means consisting of an embossment on one end of each of said sections and a plurality of indentations on the other end of some of said sections and on one end of the keeper.

7. In combination, a paint brush element and an articulated handle thereto comprising a brush element retaining means, plurality of pivotally connected sections, a universal joint connecting said sections with said retaining means, a keeper adapted to slidably receive said sections, said sections and keeper being adapted to assume angular positions in relation to each other, and means for holding said sections and keeper in said angular positions.

8. A brush comprising a brush element, an articulated handle and a means for connecting the same; said articulated handle consisting of plurality of pivotally connected sections and a keeper in form of a channel and having its longitudinal sides bent over toward the center thereof, said sections being adapted to be slid into said keeper; means for connecting said sections and keeper; and means for holding said sections and keeper in selected angular positions.

9. A brush comprising a brush element; a handle and a means for connecting the same; said handle consisting of a keeper and plurality of sections connected to each other and retractable into said keeper; said sections being adapted to extend said handle and to assume angular positions in relation to each other and to the keeper.

LEO Y. BOOHARIN.
